TWIN PHONOGRAPH

Leland D. Norton and John E. Renholdt, Bridgeport, Conn., assignors to Dictaphone Corporation, New York, N. Y., a corporation of New York

Application April 14, 1932, Serial No. 605,202
Renewed June 29, 1934

21 Claims. (Cl. 274—18)

This invention relates to twin-phonographs for recording lengthy speeches, telephone conversations and the like; and more particularly to means for controlling the alternate operation of the units thereof.

One of the objects of the invention is to provide a simple and reliable control for twin-phonographs for alternating the operation of units. Another object of the invention is to provide an adjustable control for the respective electrical elements of the units of a twin-phonograph for causing alternate operation of the twin units of the phonographs in such a way as to provide an adjustable predetermined degree of repetition of the material being recorded as one unit finishes a recording operation and the other unit starts a recording operation. A further object is to materially increase the efficiency of the active recording unit by ensuring uniformity of magnetic energization. Another object of the invention is to provide a control of the nature described for reliably de-energizing the electrical recorder of a unit when power for driving that unit is cut off.

Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which are shown one of the various possible embodiments of this invention,

Fig. 1 is a vertical section of a twin-phonograph embodying the present invention, taken substantially on line 1—1 of Fig. 2;

Fig. 2 is a plan and section taken substantially on line 2—2 of Fig. 1; certain parts being broken away to show a feature of our invention comprising circuit changing means in position to render both units operative;

Fig. 3 is a vertical section taken on line 3—3 of Fig. 1;

Fig. 4 is an enlarged section taken on line 4—4 of Fig. 3 containing diagrams of circuits controlled by our circuit changing mechanism;

Fig. 5 is a view showing the switches of Fig. 4 in a position to render unit A operative and unit B inoperative;

Fig. 6 is a fragmentary plan view of our switch control mechanism in the position it will occupy when the unit A is recording and the unit B is

inoperative, and just before the switch mechanism is actuated to set the unit B in operation;

Fig. 7 is a view similar to Fig. 6 but showing the switch mechanism shifted to render the unit A inoperative and the unit B operative; and,

Fig. 8 is a view similar to Figs. 6 and 7 showing the condition of the switch mechanism when both units have been rendered inoperative by each respective carriage reaching the end of its recording travel.

Corresponding reference characters refer to corresponding parts throughout the several views of the drawings.

Before describing the present invention in detail, it may be well to give consideration to certain of the more general aspects of twin-phonograph operation and control. One of the principal uses of this type of machine is to record continuously, matter of too great length to be included on a single record tablet. Accordingly, two duplicate phonograph units are employed, each having a mandrel for a record tablet, and each mandrel being associated with a carriage which supports a recorder carrying a stylus for recording upon a sound record mounted thereon. Mechanism is employed for causing the alternate operation of the two units in such a manner that when the record tablet on the mandrel of one machine is exhausted, or its limits reached, the other machine or unit will automatically be put into operation. The first tablet now may be removed, and a third substituted therefor. This alternate operation of the machines, and substitution of record tablets, may be continued until the end of the speech or message, or as long as the operator desires.

The present invention provides a novel arrangement of electrical and mechanical elements which may be operated automatically to supply energy or power to drive the second phonograph unit to start recording, when the recorder of the first phonograph unit which has previously been put in operation, approaches the end of its record-cylinder, and subsequently to cut off the supply of electrical energy for driving the first unit. While the supply is thus cut off from the first unit, the latter may be reconditioned for recording by substituting a new record for the used tablet and returning the recorder to starting position. As the carriage of the second machine reaches the end of its sound record, it automatically closes the electrical circuit of the first unit, and starts its operation, and subsequently cuts off the source of driving energy from the second unit.

In the present embodiment, the sound is recorded on the record-cylinder by means of an electrical recorder which is energized by a modulated current received from an amplifying system such as, for example, that disclosed in United States Patent No. 1,823,717 to H. S. Worrell, issued September 15, 1931. Each of the twin-phonograph units receives current from the same amplification unit. The present invention provides a novel arrangement of electrical and mechanical means for connecting the recorder of either unit to the amplifier when that unit is set in operation, as described above, and subsequently disconnecting the recorder of the said unit simultaneously with discontinuance of the drive thereof.

The twin-phonograph shown in the present drawings comprises a sub-base 1 which is hinged or otherwise mounted on a support (not shown). Upon the sub-base 1, a pair of base-plates 3 are suitably secured to the base 1, side by side, by screws 5. A pair of duplicate phonograph units, hereinafter referred to as unit A and unit B, are mounted upon the base-plates. In the following description, it should be understood that the details described with reference to one unit are exactly duplicated in the second unit. Each of the phonograph units comprises a housing 7 which provides a bearing for a rotatable mandrel 9 and for a freely rotatable pulley 11. The mandrel 9 is adapted to support a record-cylinder 13 of wax-like material, upon which a helical sound groove may be engraved by means of a recording stylus 15 in a well-known manner.

Near the right end of the base-plate 3 a front standard 17 and a back standard 19 are located, see Fig. 2. Between these standards and the housing 7 there is supported a front carriage rod 21, a back carriage rod 23, and a rotatable feed-screw 25. Upon the rods 21 and 23, and adapted to be moved longitudinally of the record-support or mandrel 9, a recorder carriage 27 is located. The recorder carriage supports an electro-magnetic recording device of any suitable construction.

A brief description of the assembly and operation of the pulley 11, the mandrel 9, the carriage 27, and the feed-screw 25 is as follows:

The pulley 11 is preferably driven by an electric motor indicated at 31, by means of a driving belt 33. The pulley 11 drives the mandrel 9 directly, through a suitable driving shaft (not shown) and also drives the feed-screw 25 from the mandrel shaft through a suitable train of gears (not shown), and with a proper change in speed whereby the carriage 27 may be moved longitudinally along the rods 21 and 23 at a desired rate. A driving connection between the feed-screw 25 and the carriage 27 is effected by means of a feed-nut 35 suitably pivoted by a pin 37 in a U-shaped slot 39 formed in the carriage 27. The feed-nut 35 is controlled by a control lever 41, also rotatably mounted in the U-shaped slot 39. When the control lever 41 is raised, a lobe 45 engages a knob portion 47 of the feed-nut 35 and rotates the feed-nut to lift it out of engagement with the feed-screw 25, and at the same time a lobe 49, also on the control lever 41, engages a pivotally mounted stylus-carrier 51 to lift the stylus 15 out of engagement with the record-cylinder 13. In normal operation of the machine the recorder carriage starts its operation at its farthest position to the left. Although this position is not shown, it is substantially indicated by the position of the carriage extension

bar 26 of the unit B machine in Fig. 2. At the start of the operation a handle 40 of the control lever 41 is lowered so that the recording stylus 15 is also lowered into engagement with the record-cylinder 13 and the feed-nut 35 is yieldingly held in engagement with the feed-screw 25 by means of a spring 53, as shown in Fig. 1. The operation of the machine is so controlled that under normal operating conditions the carriage drive for each unit is automatically stopped before the feed-nuts 35 run off of the threaded portion of the feed-screw 25.

As shown in Fig. 4, the recorder 29 of each unit A and unit B is connected with a power amplification unit generally indicated at 59. The one power amplifier may be connected to supply either or both of the recorders 29 with sound wave modulated electric current. There is also shown connected with the power amplification unit 59 a microphone 61, for translating sound waves into electrical current modulations.

The wiring system for the motors 31, and for the amplifying means, is diagrammatically shown in Fig. 4. The motors 31 are preferably driven by means of the usual electrical energy supplied to an office building or the like, indicated by main power lines 63 and 65. The motors 31 are connected with the main lines through a main switch 69 and terminals 73 and 75. The circuit connecting the motor 31A of unit A with the terminals 73 and 75 is as follows: a lead 77 connects the terminal 73 with the motor 31A, a lead 79 connects the motor 31A with a change-over switch generally indicated at index S, and a return lead 81 connects the switch S with the terminal 75.

The motor 31B of the unit B machine is connected with the terminals 73 and 75 as follows: a wire 85 connects the motor 31B with the switch S, and the return wire 81 connects the switch S with the terminal 75; a wire 83 connects motor 31B with the terminal 73.

The power amplifier 59 is connected with the recorders 29A and 29B of the units A and B respectively as follows: a line 87 provides an electrical connection between the amplifier and a change-over switch generally indicated by index S'; a line 89 connects the switch S' with the recorder 29A of the unit A machine. A line 91 connects the switch S' with the recorder 29B of the unit B machine. A common return line 93 connects the recorders of both units A and B with the power amplifier 59.

It is desirable that the switches S and S' should be able to connect either or both of the motors of the units A and B with the power line, and either or both of the recorders of the units A and B with the amplifier 59. For accomplishing such a result I may use any of the known mechanical switches, but in the present embodiment of the invention I have found it expedient to use mercury switches such as are shown in Figs. 1, 3, 4 and 5. As the switches S and S' may be identical, it is necessary to describe only one. The switch S comprises a tubular-shaped container 95, preferably formed from some dielectric material such as glass, having wells or hollow projections 97, 99 and 101 extending from the bottom thereof, as shown in Fig. 4. The container 95 is sufficiently filled with a fluid electrical conductor such as mercury 103, so that when the container 95 is in a level position and the wells 97, 99 and 101 are extending downwardly, the mercury 103 will fill all of the wells, and stand above the top of the wells to provide an electrical

connection between them all. The container is mounted so that it can be tipped at an angle to the horizontal, causing the mercury 103 to flow to the lowered end thereof, when the upper well 5 will be cut off from the other two. For example, the switch S is shown in a tipped position in Fig. 5, in which the wells 97 and 99 are lowered and the mercury 103 has flowed to the lowered end to break the mercury connection between the well 101 and the other remaining wells 97 and 99.

The interior of the wells 97, 99 and 101 are connected with the leads or wires 79, 81 and 85 respectively. It is evident, with the switch S in the position shown in Fig. 4, and with the switch 15 69 closed, that electrical energy will be supplied from the lines 63 and 65 to the motors 31A and 31B rendering both units operative to travel along their respective record-cylinders. But, by tipping the switch S, as shown in Fig. 5, the electrical connection to the motor 31B of the unit B machine is broken, rendering the B machine inoperative. Also, it is evident that by tipping the switch S in the opposite direction, the motor 31A of the A unit will be disconnected, putting the 20 A unit out of operation.

The supply of electrical energy to the terminals 73 and 75, and consequently to both of the motors 31, may be discontinued by the manually controlled switch 69.

As above pointed out, the switch S' is identical in construction to the switch S; and it is clear that both of the recorders 29A and 29B of the unit A and B machines are electrically connected with the amplifier 59 when the switch S' is in the 35 position shown in Fig. 4.

The electrical energy from the amplifier 59 enters the well 99', flows through mercury 103' to the well 97', to the recorder 29A of the unit A machine by wire 89, and then back to the amplifier 59 by the common return lead 93. Likewise, the well 99' is connected with the well 101' by the mercury 103' and the current flows from the well 101' to the recorder 29B of the unit B machine over the wire 91, and thence to the amplifier 59 by the common return lead 93.

In the Figure 5 position of the switch S' the recorder 29B of the unit B machine is cut out while the recorder 29A of the unit A machine is left in. When the switch S' is tilted to lower the well 101' the unit A machine sound recorder is cut out and the recorder of the unit B machine cut in.

From the above description, it is clear that a novel switching arrangement is provided for the simultaneous control of the motors 31 and the recorders 29 of the unit A and B machines, whereby either or both of the motors 31 may be energized, and either or both of the recorders 29 may be connected with the amplifier 59.

I will now describe certain other novel features of the invention by which the switches S and S' are controlled or positioned to effect an alternate operation of the units A and B. The switches S and S' are mounted upon an oscillating arm or lever 107 pivotally mounted near its center upon a bracket 109 by means of a stud 111. Bracket 109 is adjustably mounted on the under side of the sub-base 1 by means of screws 110 (Fig. 2) which pass through slots 112 formed in the bracket 109. It is evident from the manner in which the bracket 109 is thus mounted on the sub-base 1 that the position of the bracket 109 may be adjusted longitudinally of the sub-base 1 by loosening the screws 110 and sliding the bracket 109 in one direction or the other so that

the screws 110 assume intermediate positions in the slots 112.

The switch S is mounted at the upper end of arm 107 by spring clips 113. The switch S' is secured to the lower arm of the lever 107 by means of similar clips 113. Thus, as the lever 107 pivots about the stud 111, the containers 95 and 95' of the switches S and S' respectively are tipped, so that the mercury flows to the lefthand ends of the containers when the lever 107 is swung in a counter-clockwise direction (as viewed in Fig. 4), and to the righthand ends of the containers when the lever 107 is swung in the opposite direction.

A description of the mechanism for controlling the circuits which contain mercury switches S 15 and S' is as follows (see Figs. 1, 2 and 3):

A lever 117 is pivotally mounted adjacent one end on the underside of the sub-base 1 between the twin machines by means of a stud 119. At the end of the long arm of the lever 117 is a post 121, which extends through a slot 123 formed in the base 3, sufficiently far to be in the path of the extension bar 26 of the carriage 27 of the unit A machine. The pivoted end of the lever 117 has an angle portion 125 extending at right angles 25 to the main lever 117. A similar lever 127 for the unit B machine is also pivoted near one end upon the stud 119; and at the other end is provided a post 129, which extends through slot 123 in the base-plate into the path of the carriage 30 arm 26 of the unit B machine. The pivoted end of the lever 127 also has an angle portion 131 extending therefrom, as is clearly shown in Figs. 2, 6, 7 and 8. It is evident that the levers 117 and 127 may be swung about the stud 119 by the contact of the carriage extension bars 26 of the units A and B respectively. The carriage arm 26 of the unit A machine is adapted to move the arm of the lever 117 about the stud 119 in a counter-clockwise direction (as viewed in Fig. 2). The carriage arm 26 of the unit B machine is adapted to move the lever 127 about the stud 119 in a clockwise direction (as viewed in Fig. 2). The levers 117 and 127 are spaced from the sub-base 1 by means of a collar 120.

The motion of the arms or levers 117 and 127 is transmitted to the switch lever 107 by means of a connecting lever 133, and a motion multiplying lever 135. The lever 133 is pivoted near one end on the stud 119, and is located beneath the two levers 117 and 127. The mechanical interconnection between the levers 117, 127 and 133 is made resilient as follows: the pivoted end of the connecting lever 133 has a turned up end or finger 137, against which the opposing edges of the angle portions 125 and 131 of the levers 117 and 127 abut. The proportioning of the width of the finger 137 and the portions 125 and 131 is such that when the latter portions are abutted against the finger 137, the levers 117 and 127 are aligned with each other. The levers 117 and 127 are normally held in this aligned position, by means of a tension spring 139 which extends between and is connected to the angle portions 125 and 131 of said levers. It is evident that the levers 117 and 127 constitute in effect a single lever, the arms of which, although normally restrained in a straightline position, may be independently swung about the stud 119 by the respective carriage bars, the arm 117 in a counter-clockwise manner and the arm 127 in a clockwise manner. Further, the single lever which is thus formed by the arms 117 and 127 yieldingly transfers its motion to the connecting link 133, through 75

the action of the angle portions 125 and 131 on the finger 137.

The multiplying lever 135 is pivoted above its center to the bracket 109 by means of a stud 145. It has a finger 134 extending from the top thereof, and passing through a slot 143 formed in the free or long arm of the connecting lever 133. Thus the movement of the connecting lever 133 about the stud 119 is transferred to the motion-multiplying lever 135. The latter lever transfers its motions to the lever 107 by means of a pin 147 mounted on the lever 107, a little above the stud 111. The pin 147 extends through an opening 149 formed in the bracket 109, and into a slot 151 formed in the lower end of the motion-multiplying lever 135.

The operation of the lever and switch system will be described in connection with Figs. 2, 6, 7 and 8, which show the different positions which the parts assume under different conditions of operation of the twin-machine.

Record-cylinder blanks 13 are placed on the mandrels 9 of the phonograph units A and B, and the recorder carriages 27 are moved to the starting position (the left-hand position as shown in Fig. 2 by the carriage arm 26 of the unit B). Then the control levers 41 of both units are manipulated to position the styli to engage their respective record-cylinders, and the feed-nuts to engage their respective feed-screws. Both units are now in condition to operate whenever the respective mandrels are set in operation by the respective motors 31. The units A and B as described may be used for the purpose of recording telephone conversations and messages; therefore it should be understood that the recorders 29 may be of any suitable construction designed for electrical recording and may be connected by any suitable means to divers kinds of sound sources.

After the recorders are conditioned for sound-recording, the operator, if he desires to have the unit A operate, rather than the unit B, sets the lever system to the position shown in Fig. 6 to swing the switches S and S' to the position shown in Fig. 5, in which position the motor 31 of the unit A is electrically connected with the terminals 73 and 75 through the switch S and the recorder 29 of the unit A is electrically connected with the amplifier 59. As hereinbefore pointed out, in this position of the parts the electrical connection is broken between the motor 31 of the unit B machine and the terminals 73 and 75 and the recorder 29 of the unit B machine is also disconnected from the amplifier 59. If now the operator closes the switch 69, the electrical energy from the main lines 63 and 65 is available to the motor 31 of the unit A and the unit A machine is placed in full recording operation.

The belt 33 is caused to travel under the influence of the driving pulley 57, to rotate the pulley 11, to drive the mandrel 9, and the feed-screw 25. With this operation of the machine, the recorder 29 of the A unit will travel over the record to cut a spiral sound groove. The sound groove records the sound waves picked up by the microphone 61, and it will be particularly noted hereinafter how the twin-phonograph machines function to make possible a continuous record of a telephone conversation, public speeches, etc.

The carriage arm 26 of the recorder carriage 27 of the phonograph unit A, as it travels toward the end of the record-cylinder, engages the upstanding stud or post 121 (Fig. 6), and as the carriage 27 and the arm 26 continues to travel toward the end of the record, the arm 26 moves

the stud forwardly (in the direction of the arrow as indicated in Fig. 6). In this way, the lever 117 is moved counterclockwise around the stud 119. Because of the tension of spring 139, lever 127 moves with lever 117 to maintain its alignment therewith and cause rotation of lever 133 about pivot 119. By this motion of the connecting lever 133 the motion-multiplying lever 135 is moved about the stud 145, and the motion of the multiplying lever 135 is transferred to lever 107, to gradually move the switches S and S' from the Fig. 5 and Fig. 6 position to the Fig. 2 and Fig. 4 position. As a result the switches S and S' connect the unit B machine with the respective sources of electrical energy, and the unit B machine is set in recording operation. It is to be noted that as hereinbefore pointed out, the switches S and S' in the Fig. 4 position (in the mid position) connect both of the units A and B with electrical energy and consequently both of the machines are operated simultaneously.

Continued operation of the unit A machine, however, advances the carriage arm 26 still farther toward the end of its travel and this continued movement of the arm 26 moves the levers 117, 127 and 133 about the stud 19 to move the arm 107 to such a position as to tip the switches S and S' and disconnect the motor 31 and the recorder 29 of the unit A machine from their respective sources of power, and accordingly the recording operation of the unit A machine is stopped. This position of the lever system is shown in Fig. 7, and it is noted that in this position the posts 121 and 129, and their respective arms or levers 117 and 127 are in a position directly opposite from that shown in Fig. 6.

Thus for a short interval, during the movement of the switches S and S' through an arc, both machines A and B are operated; several factors are involved in determining the length of the interval during which both of the machines are operated by the switches S and S'. It is preferable that these factors be correlated in such a fashion that an overlap of from four to eight sound grooves be effected. The amount of overlapping, however, may be changed as desired, by changing the correlation between the factors; for example, if a longer overlapping period is desired, the mechanical advantage of the connecting lever 133 may be changed, thus making a greater throw of the arm 117 necessary to shut off the motor of the unit machine which is just finishing its recording operation.

As the recording operation of the unit B machine now continues, the unit A machine may be reconditioned for recording by changing the old record for a new record, and positioning the recorder carriage 27 in its starting position, at the left of the machine.

As the recording operation of the unit B machine continues, the carriage arm 26 of the unit B machine moves forward, as shown in Fig. 7, until finally it contacts with the upstanding stud or post 129. Further motion of the arm 26 now moves the post 129 forwardly to move the arm 65 or lever 127 in a clockwise manner, whereby the arm or lever 107 is moved in a counter-clockwise manner about the stud 111, and the switches S and S' are moved to neutral position and the unit A machine is restarted. As before, the two machines A and B now operate simultaneously during the overlapping period. However, the continued movement of the arm 26 of the unit B machine moves the post 129 forwardly to return the switches S and S' to the position shown in Fig. 6.

Fig. 5, in which position the unit B machine is cut off from all electrical energy.

Although in Fig. 7 the carriage arm 26 of the unit A machine is shown in contact with the up-standing post 121, it is to be understood that in the usual operation of the two machines as a unit, the carriage 27 of the unit A machine would have been repositioned in starting position, and accordingly the arm 26 would not be in the position shown in Fig. 7 but in a position similar to that of the arm 26 of the unit B machine in Fig. 2.

From the above description it is clear that the units A and B may be operated to record a lengthy speech or other matter without interruption, and that when the respective carriages reach the ends of their recording operations, one machine will be put into recording operation before the other machine is stopped; there is no opportunity for any hiatus occurring in the recording of a speech. Further, the amount of overlapping may be nicely adjusted at the factory, or later by the operator, by changing the position of the bracket 109 with respect to its spacing from the stud 119 whereby the mechanical advantage between the levers 117 and 127 and the finger 134 of the multiplying lever 135 is changed. By moving the bracket 109 closer to the stud 119 the mechanical advantage may be reduced, and a longer time interval or overlap provided between the starting of one of the machines and the stopping of the other. By moving the bracket away from the stud 119 the mechanical advantage may be increased and the length of the period of the overlapping interval may be reduced.

The purpose and operation of the resilient connection between the levers 117 and 127 and the connecting link or lever 133, and consequently the resilient connection between the connecting link 133 and the carriage arms 26 of the unit A and B machines may be described as follows:

Although under normal operation of the two machines A and B as a unit, the machine which has just finished its recording operation is returned to its starting operation while the other machine is continuing its recording operation, it is possible that the operator may forget to recondition the machine which has just completed its record, in which event both of the carriage arms 26 may reach the finish position, as shown in Fig. 8. Now if some precaution were not taken, or if the arms 117 and 127 were parts of a rigid lever, the approaching arm 26 of the unit B machine, referring to Fig. 8, would tend to move the lever 127 in a clockwise manner about the stud 119. But the movement would be resisted by the pressure of the arm 26 of the unit A machine against the post 121. (It is assumed for the purpose of explanation that the arm 26 of the unit A machine was left in its finished recording position, in Fig. 8, with its feed-nut 35 in contact with the threaded portion of its feed-screw 25, and that the arm 26 of the unit B machine moved to its finished recording position subsequent to the finishing of machine A.) It is evident that if the levers 117 and 127 constitute a rigid lever, the continued movement of the arm 26 of the B machine toward the position of Fig. 8 might cause breakage of some part of the machine, burn out a motor or do other damage. However, my resilient leverage system provides against such damage in the event that the operator forgets to recondition the machine which has just finished its recording operation.

As hereinbefore described, the action of the

spring 139 holds angle portions 131 and 125 of the arms 127 and 117 respectively against the finger 137, and although the arms 117 and 127 are normally restrained in a straightline position, and although the connecting link 133 is normally restrained in a position which is substantially perpendicular to the arms 117 and 127, they may be moved from this normal position under the peculiar circumstances set out above. Thus, assuming that in the Fig. 8 position the arm 26 of the unit A machine were left in its finished recording position, then forward movement of the arm 26 of the unit B machine rotates the arm 127 in a clockwise manner about the shaft 119; but because the arm 26 of the unit A machine resists the corresponding clockwise and reverse rotation of the movement of the arm 117, the latter arm remains stationary, and the angle portion 131 of the arm 127 moves out of contact with the finger 137 of the connecting lever 133, against the action of the spring 139, which is now stationary. As a result the lever 107 on which the switches S and S' are mounted is not moved and the switches remain in the same position, namely, connecting only the unit B machine with the respective sources of power, while the levers 117, 127 and 133 assume the position shown in Fig. 8.

Consequently, the unit B machine continues its operation without restarting the unit A machine, and the recorder carriage 27 continues its advance until the feed-nut 35 reaches the end of the threaded portion of its feed-screw 25, at which point the forward motion of the carriage 27 ceases, although the motor 31 of the unit B machine continues to rotate.

From the above operation, it is clear that no damage will result to the machine in the event that the operator forgets to return an inactive recorder to its starting position. The result would be merely to cause the motors to run idle until such condition be discovered and remedied.

The above overlapping feature described for the two phonograph units, as pointed out, is particularly desirable when recording lengthy telephone conversations, etc. The arrangement enables the transcriber to determine the proper sequence of cylinders (or relationship of cylinders) because the first few words of one cylinder will correspond exactly with the last few words of the preceding cylinder.

An advantage of the present embodiment of the invention is the arrangement of the two units A and B side by side, with their respective mandrel shafts pointing in the same direction, and the return movement of the carriage 27 is also in the same direction. Thus the operation of the two units is simplified, and the possibility of the operator becoming confused in the manipulation of the machine is eliminated. In fact, the machines may be more effectively and accurately operated than twin-phonographs arranged with their mandrels in coaxial alignment but extending in opposite directions.

By the provision of separate motors for the individual units, a more positive operation is obtained than was possible with the usual construction. It will be appreciated, too, that by disconnecting the idle recorder from the amplifier there will be less current drain on the amplifier and steadier and more efficient operation of the active recorder unit.

From the foregoing, it will be seen that there is provided a construction of an essentially prac-

tical nature, well adapted to attain the several objects of this invention.

As many possible embodiments may be made of the above invention without departing from the scope thereof, it is to be understood that all matter herein set forth or shown in the accompanying drawings is to be interpreted as illustrative and not in a limiting sense.

We claim:

- 10 1. In apparatus of the class described, in combination, two sound-recording machines mounted on a common base, each machine having a sound-record support, a recorder carriage, and an electric motor for driving the sound-record support and carriage; a source of power for said motors; a switch for connecting said power with either or both of said motors; and a system of mechanically connected levers capable of establishing a mechanical connection between said carriages and said switch as said carriages approach the end of a recording operation.
- 15 2. In apparatus of the class described, in combination, two sound-recording machines mounted on a common base, each machine having a sound-record support, a recorder carriage, and an electric motor for driving the sound-record support and carriage; a source of power for said motors; a switch for connecting said power with either or both of said motors; and a system of mechanically connected levers capable of establishing a mechanical connection between said carriages and said switch as said carriages approach the end of a recording operation, whereby as one machine finishes its recording operation it is mechanically interconnected with said switch and moves said switch to start the recording operation of the second machine and subsequently to stop the recording operation of the first machine.
- 20 3. In apparatus of the class described, in combination, two sound-recording machines mounted on a common base, each machine having a record-support and a carriage, and driving means for rotating said record-supports and for driving said carriages longitudinally with respect to said record-support; a source of power for said driving means; a double throw switch for connecting said source of power with either or both of said driving means; and means for changing the position of said switch to start the recording operation of one machine as the other machine finishes a recording operation, and then subsequently to stop the recording operation of the finishing machine, said means being operable by the carriages of the respective machines in succession.
- 25 4. In apparatus of the class described, in combination, two sound-recording machines mounted on a common base, each machine having a record-support and a carriage, and driving means for rotating said record-supports and for driving said carriages longitudinally with respect to said record-support; a source of power for said driving means; a switch for connecting said source of power with either or both of said driving means; and means for changing the position of said switch to start the recording operation of one machine as the other machine finishes a recording operation, and then subsequently to stop the recording operation of the finishing machine, said means comprising a system of mechanically connected levers capable of establishing a mechanical interconnection between said carriages and said switch as said carriages respectively approach the end of a recording operation.

5. In apparatus of the class described, in combination, duplicate successively operable sound-recording machines, each comprising a record-support and a recorder carriage and each being driven by a separate electric motor; a pivotally mounted switch for connecting a source of power with either or both of said machines; and means for changing the position of said switch to start the recording operation of one machine as the other machine finishes a recording operation, and then subsequently to stop the recording operation of the finishing machine, said means comprising a jointed and resiliently biased lever mounted on a pivot, a connecting lever also mounted on said pivot and capable of rocking said switch, said connecting lever being constrained to rotate with said jointed lever about said pivot, and means on said jointed lever positioned in the paths of travel of said carriages.

6. In apparatus of the class described, in combination, duplicate successively operable sound-recording machines, each comprising a record-support and a recorder carriage and each driven by a separate electric motor; a pivotally mounted switch for connecting a source of power with either or both of said machines; and means for changing the position of said switch to start the recording operation of one machine as the other machine finishes a recording operation, and then subsequently to stop the recording operation of the finishing machine, said means comprising a jointed lever mounted on a pivot, a connecting lever also mounted on said pivot, and capable of rocking said switch, said connecting lever being resiliently constrained to rotate with said jointed lever about said pivot, and upstanding abutments mounted on the free ends of said jointed levers capable of intercepting the path of said carriage, whereby each carriage moving into finishing position contacts with its respective abutment and the interconnecting lever changes the position of the switch to start the other machine in recording operation, said jointed lever and interconnecting lever being adapted to prevent injury to the machines should both carriages reach the finishing position.

7. In apparatus of the class described, in combination, duplicate normally successively operable sound-recording machines, each comprising a record-support and a recorder carriage and each driven by a separate electric motor; a switch for connecting a source of power with either or both of said machines; and a lever system for mechanically connecting said carriages with said switch, whereby as the carriage of one machine finishes its recording operation the motion of said carriage changes the position of said switch to start the operation of said second machine and subsequently to stop the recording operation of the first machine, said lever system comprising two levers resiliently connected to act as a single lever pivoted at its center, abutments carried by said single lever on either side of said center, each abutment being capable of contacting with one of said carriages, the arrangement being such that when one abutment is contacting with its carriage the other abutment is free to move under the influence of the contacting abutment, but in the event that both carriages contact with their respective abutments, the abutments may move independently of one another because of the resilient connection of said levers.

8. In apparatus of the class described, in combination, two sound-recording machines mounted on a common base, each having a record-

support, a movable carriage, and independent driving means for rotating the record-support and for moving the carriage longitudinally of the record-support; a source of power for said driving means; and means comprising a fluid switch operable by one of said carriages as it reaches a predetermined position with respect to its record-support to start the second record-support and carriage by connecting the driving means of said second carriage with said source of power, and for cutting off said source of power from said first-named driving means as said first-named carriage reaches a second predetermined point, and means whereby said fluid switch may be operated for successive reversals by the carriages of the respective machines.

9. In apparatus of the class described, in combination, two sound-recording machines mounted on a common base, each having a record-support, a movable carriage, and independent driving means for rotating the record-support and for moving the carriage longitudinally of the record-support; a source of power for said driving means comprising a rockable fluid switch; and means for connecting said source of power to either or both of said driving means, said means being operable by one of said carriages as it approaches the end of its record to start the other carriage and record-support by connecting said source of power with the other driving means, and being further operable to stop said first carriage and record-support as said carriage moves farther toward the end of said record-support, said means being operable successively first by one carriage and then by the other to produce continuously successive operation of said machines.

10. In apparatus of the class described, in combination, two sound-recording machines mounted on a common base, each having a record-support, a movable carriage, and independent driving means for rotating the record-support and for moving the carriage longitudinally of the record-support; a source of power for said driving means; and means for connecting said source of power to either or both of said driving means, said means being operable by one of said carriages as it approaches the end of its record to start the other carriage and record-support by connecting said source of power with the other driving means, and being further operable to stop said first carriage and record-support as said carriage moves farther toward the end of said record-support, and said means also being operable by said second carriage to start said first-named carriage, and to stop said second carriage.

11. In apparatus of the class described, in combination, two sound-recording machines mounted on a common base, each having a record-support, a movable carriage, and independent driving means for rotating the record-support and for moving the carriage longitudinally of the record-support; a source of power for said independent driving means; a switch for connecting either or both driving means to said source of power, a lever system responsive to carriage operation for operating said switch, said switch being operable by means of said lever system by one of said carriages as it approaches the end of its sound-record to connect the source of power with the driving means of the other carriage to start said other carriage at the beginning of a record, and upon continued movement of said first-named carriage to disconnect said source of

power from the driving means of said first-named carriage.

12. In apparatus of the class described, in combination, two sound-recording machines mounted on a common base, each having a record-support, a movable carriage, and independent driving means for rotating the record-support and for moving the carriage longitudinally of the record-support; a source of power for said driving means, switch means for connecting either 10 or both of said driving means to said source of power, a lever system responsive to carriage operation for operating said switch, said switch being operable by means of said lever system by one of said carriages as it approaches the end 15 of its sound-record to connect the source of power to the driving means of the other carriage to start said other carriage, and upon continued movement of said first-named carriage to disconnect said source of power from the driving means 20 of said first-named carriage, and said second-named carriage as it approaches the end of its sound-record being adapted to operate said switch by means of said lever system to connect the source of power with said first-named driving 25 means, to start said first-named carriage and upon further movement of said second-named carriage to disconnect said source of power from the driving means of said second-named carriage. 30

13. The combination of two duplicate successively operated sound-recording machines, each comprising a record-support, a recorder carriage, and an electric driving motor, and means comprising a pair of co-pivotal levers spring-biased 35 normally to act as a single lever responsive to the operation of said carriages for controlling connections to said motors to control the said operation of said carriages.

14. The combination of two duplicate successively operated sound-recording machines, each comprising a record-support, a recorder carriage, and an electric driving motor and means comprising a pair of co-pivotal levers spring-biased normally to act as a single lever responsive to the 45 operation of said carriages for controlling connections to said motors to control the said operation of said carriages, and respectively independently operable in response to operation of said carriages without effect upon the connections to said motors and the operation of said carriages. 50

15. The combination of two duplicate successively operated sound-recording machines, each comprising a record-support and a recorder carriage, means comprising a pair of co-pivotal levers spring-biased normally to act as a single lever, a change-over switch for controlling the operation of said carriages, and means for effecting the 55 operation of said switch by one of said levers when the other of said levers is actuated by one of said carriages. 60

16. The combination of two duplicate successively operated sound-recording machines, each comprising a record-support and a recorder carriage, a pair of co-pivotal levers, a spring connecting said levers normally compelling action thereof as a single lever, a change-over switch for controlling the operation of said carriages, and 70 means for effecting the operation of said switch by contact with one of said levers when the other of said levers is actuated by one of said carriages, said other lever being incapable because of said spring connection effecting the operation of said 75

switch through contact with said means so long as the said one lever is effective.

17. The combination of two duplicate successively operated sound-recording machines, each comprising a record-support, an electrical recorder and a recorder carriage; electrical driving means for each of said machines; electrical energizing means for said recorders; a switch for controlling the operation of said driving means; a switch for connecting said energizing means to said recorders; means mounting said switches for simultaneous operation, and means responsive to operation of said carriages for actuating said switches.

18. In apparatus of the class described, in combination, duplicate sound-recording machines each having a record-support, a carriage, and driving means for rotating the record-support and driving the carriage; a source of power for said driving means; a switch movable between extreme positions for connecting said source of power with either, through a mid position for connecting said source of power with both of said driving means; a system of motion-transmitting elements for shifting said switch comprising a pair of reciprocatively and rotatively connected levers adapted to pass through a dead center position to cause a reduced rate of motion of said switch during the mid portion of its movement from one extreme position to the other; and means responsive to operation of said carriages for actuating said system of elements.

19. In apparatus of the class described, in combination, duplicate sound-recording machines each having a record-support, a carriage, and driving means for rotating the record-support and driving the carriage; a source of power for said

driving means; a switch movable between extreme positions for connecting said source of power with either or both of said driving means; a system of motion-transmitting elements for shifting said switch comprising a pair of reciprocatively and 5 rotatively connected levers adapted to pass through a dead center position to cause a variation in the rate of motion of said switch during its movement between said extreme positions; and means responsive to the operation of said carriages for actuating said system of elements.

20. In apparatus of the class described, in combination, duplicate sound-recording machines each having a carriage and driving means adapted to move the carriage at a substantially uniform 15 rate; a source of power for said driving means; a switch for connecting said source of power with either or both of said driving means, and mechanism actuatable successively by the respective carriages to cause the uniform movement of the carriages to impart movement to said switch at a 20 variable rate.

21. In apparatus of the class described, in combination, two sound-recording units each having a sound-recorder carriage and an electric motor 25 for driving the carriage; a source of power for said motors; a switch for connecting said power with either or both of said motors; and a mechanical transmission system capable of establishing a connection for transmitting motion between said 30 carriages and said switch as said carriages approach the end of a recording operation, said system comprising means for adjusting the system to transmit motion at different predetermined rates.

LELAND D. NORTON.

JOHN E. RENHOLDT.

CERTIFICATE OF CORRECTION.

Patent No. 2,026,398.

December 31, 1935.

LELAND D. NORTON, ET AL.

It is hereby certified that error appears in the printed specification of the above numbered patent requiring correction as follows: Page 7, first column, line 24, claim 9, strike out the words "comprising a rockable fluid switch" and insert the same after "means" in line 25, same claim; and second column, line 75, claim 16, before "effecting" insert of; and that the said Letters Patent should be read with these corrections therein that the same may conform to the record of the case in the Patent Office.

Signed and sealed this 3rd day of March, A. D. 1936.

Leslie Frazer

(Seal)

Acting Commissioner of Patents.
